DESIGN FOR A COMBINED SLIDER BODY
AND PULL TAB BAIL FOR SLIDE FASTENERSNoel J. Poux, Meadville, Pa., assignor to Talon,
Inc., Meadville, Pa., a corporation of Pennsylvania

Application July 2, 1938, Serial No. 78,255

Term of patent 14 years

To all whom it may concern:

Be it known that I, Noel J. Poux, a citizen of the United States, residing at Meadville, in the county of Crawford and State of Pennsylvania, have invented a new, original, and ornamental Design for a Combined Slider, Body, and Pull Tab Bail for Slide Fasteners, of which the following is a specification, reference being had to the accompanying drawing, forming a part thereof.

In the drawing:

Fig. 1 is a plan view of a combined slider body and pull tab bail for slide fasteners, showing my new design.

Fig. 2 is a side view of the same.

A characteristic feature of my invention resides in the ornamental appearance of the pull tab bail and its arrangement with respect to the slider body.

I claim:

The ornamental design for a combined slider body and pull tab bail for slide fasteners, substantially as shown and described.

NOEL J. POUX.
